[57] CLAIM

The ornamental design for a Christmas tree ornament,
substantially as shown and described.

DESCRIPTION

FIG. 1 is a front elevational view of a Christmas tree
ornament, showing my new design, the rear view being
the same;

FIG. 2 is a side elevational view thereof, the opposite
side being the same;

FIG. 3 is a top plan view thereof, and

FIG. 4 is a bottom plan view thereof.
